WILLIAM G. KENDALL, OF NEWARK, NEW JERSEY, ASSIGNOR TO PARFUMERIE RIGAUD, INC., OF NEW YORK, N. Y., A CORPORATION OF NEW YORK

LIPSTICK HOLDER

Application filed February 12, 1930. Serial No. 427,850.

This invention relates to lipstick holders, and has for an object to provide an improved construction which may be made of a convenient size and which may be readily operated at the same time for ejecting or withdrawing a lipstick.

Another object of the invention is to provide a lipstick holder within a supporting sleeve which is grooved to receive a projection from a suitable cup carrying the lipstick, whereby as the sleeve is rotated the cup and lipstick may be propelled upwardly or inwardly.

A still further object, more specifically, is to provide a lipstick formed of comparatively thin sheet metal with a cup having a pressed-out pin or projection, a slotted supporting body and a grooved sleeve, the provision and arrangement of these parts being such that when the body is rotated the projection from the cup will be forced along the groove in the sleeve for propelling the cup inwardly or outwardly according to the direction of rotation.

In the accompanying drawings,—

Figure 1 is a side view of a lipstick holder disclosing an embodiment of the invention;

Figure 2 is a vertical sectional view through the structure shown in Figure 1;

Figure 3 is a transverse sectional view through Figure 2 on the line 3—3;

Figure 4 is a perspective view of the body or supporting shell shown in Figure 2;

Figure 5 is a perspective view of the cup shown in Figure 2;

Figure 6 is a view similar to Figure 2 but showing a modified construction;

Figure 7 is a sectional view through Figure 6 on the line 7—7, the same being on an enlarged scale;

Figure 8 is a perspective view similar to Figure 5 but showing the article carrier used in the form of the invention illustrated in Figure 6.

Referring to the accompanying drawings by numerals, 1 indicates a body or shell made preferably of thin sheet metal and provided near the lower end with a bead 2 over which the bottom or bottom cap 3 is forced when the parts are being assembled. Cap 3 may be

knurled exteriorly and provided with slightly inclined sides 4 which snap over bead 2 and firmly grip the body 1. Some appreciable force is necessary to force the bottom 3 into position, in order that the same may be in effect almost integral with the body 1, whereby when the bottom 3 is rotated body 1 will also be rotated. From Figures 2 and 4 it will be noted that the body 1 is provided with a straight slot 5, and through this slot extends a projecting finger 6. Preferably this projection is forced from the side walls of the cup 7, which cup normally supports the lipstick 8. If preferred, a pin or other member could be substituted for the finger 6, but preferably the finger 6 is used, as it may be readily forced from the walls of cup 7. Arranged exteriorly of the body 1 is a sleeve 9 which is rotatably mounted between the bottom 3 and the turned-over top flange 10. Sleeve 9 is provided with a pressed-out spiral portion 11 which forms a spiral groove interiorly, and into this spiral groove fits part of the finger or projection 6, as shown in Figure 2. A cap 12 is shown as slidably fitting over the upper end of the sleeve 9 but, if desired, this cap could be hinged in place without departing from the spirit of the invention. In operation after the parts have been assembled a lipstick 8 is forced into the cup 7 and then the cup 7 is moved to its lowermost position, as shown in Figure 2, unless already in this position. When the parts are as shown in Figure 2 and it is desired to use the lipstick cap 12 is removed and sleeve 9 grasped with one hand, while the other hand rotates the base 3. As base 3 is rigidly connected with body 1, this will cause the rotation of body 1 and consequently move the cup 7 and lipstick 8 upwardly, or rather, outwardly, so that the desired amount of lipstick 8 will project beyond body 1. It will be noted that the finger or projection 6 extends through section 5 and into the groove formed by member 11. The finger 6 acting against the walls of the groove will naturally cause the cup 7 to move upwardly as the parts are rotated to the right. When it is desired to retract the lipstick, base 3 is rotated to the left and the cup and lipstick automatically move to

ward the bottom of the holder. It will thus be seen that a minimum number of parts have been used and yet the lipstick is properly protected and moves in and out, as desired.

5 In Figures 6 to 8 inclusive a modified form of the invention is shown wherein the sleeve or outer casing 9' is provided with an inwardly-extending portion 11', said inwardly-extending portion being a spiral so as to present a spiral guide extending preferably from near the top to near the bottom of the shell. If preferred, the guide 11' could extend to the top and bottom, as is true of 10 the groove formation shown in Figure 1. In connection with Figure 1 it will be noted that the groove formation is provided with an offset or shoulder 12 providing a rest for the finger or pin 6. In the construction shown 15 in Figure 6 an article carrier 7' is used having an out-turned finger or section 6' formed with an opening or notch 13 which straddles the guide or internal bead 11', as shown particularly in Figure 7. The finger 6' extends 20 through the straight slot 14 similarly to finger 6 illustrated in Figure 5. In both forms of the invention there is provided an article carrier having a projecting finger, pin or other member which coacts with a guide carried by the outer sleeve or casing 9 or 9'. In 25 this way by rotating the tubular member 1 or the tubular member 15 a longitudinal movement of the article carrier will be produced.

30 35 What I claim is:—

1. A lipstick holder, comprising a sleeve having an interior spiral bead acting as a guide, a tubular body mounted in said sleeve and provided with a straight slot extending 40 from near one end to near the opposite end, an article carrier mounted within said body, and means carried by the article carrier positioned to project through said straight slot and straddle said guide, whereby upon the 45 rotation of the tubular body in one direction the article carrier will be projected from the carrier and when rotated in the opposite direction the article carrier will be withdrawn to a position within the container.

50 2. A lipstick holder, comprising a tubular body having a longitudinally-positioned slot extending from near one end to near the opposite end thereof, a bottom frictionally secured to one end of said body, a tubular sleeve 55 rotatably mounted on the outside of said body, said sleeve having a spiral bead formed on the inner surface thereof, said body having a turned-over end overlapping said sleeve so as to hold the sleeve between the turned-over end and said bottom while allowing the sleeve to freely rotate, and an article carrying member mounted in said body and provided with forked means projecting through said slot in said body into straddling engagement with said bead.

3. A lipstick holder, including a rotatable tubular member having an inwardly extending spiral projection and an article carrier formed with means straddling said projection, and a guiding member for said means 70 whereby as said tubular member is rotated said article carrier will be moved longitudinally of the tubular member.

4. A lipstick holder, including an article carrier, a tubular member acting as a guide 75 for said article carrier said tubular member having a straight longitudinal slot extending from near one end to near the opposite end and a second tubular member surrounding the first mentioned tubular member formed 80 with a spiral projection, said article carrier having means extending through said slot straddling said spiral projection, whereby when said second tubular member is rotated said article carrier will be moved longitudinally of the first-mentioned tubular member.

5. A lipstick holder, including a container provided with a spiral guide extending inwardly, a body arranged in the container provided with a straight slot and an article carrier mounted in said body provided with means extending through said straight slot into sliding straddling engagement with said guide, whereby upon the rotation of said body and the non-rotation of said container, said carrier will be propelled longitudinally of the body.

6. A lipstick holder, comprising a container having a spirally positioned bead pressed inwardly from the walls of the container, 100 a body having a straight slot rotatably mounted in said container and an article-carrier provided with projecting means straddling said bead so that when the body is rotated said carrier will be moved longitudinally 105 thereof.
